UNITED STATES PATENT OFFICE.

JOHN F. WOOD, OF BOSTON, MASSACHUSETTS.

COMBINED KNIFE-BRICK BOX AND GRINDER.

SPECIFICATION forming part of Letters Patent No. 290,619, dated December 18, 1883.

Application filed October 15, 1883. (No model.)

To all whom it may concern:

Be it known that I, JOHN FRANCIS WOOD, of Boston, in the county of Suffolk and State of Massachusetts, have invented a new and 5 Improved Combined Knife-Brick Box and Grinder, of which the following is a full, clear, and exact description.

My invention consists of a box for holding a knife-brick, having a grater-bottom, on which 10 the brick rests, and whereon the brick is always ready to be ground whenever the dust is wanted for scouring knives or any other object, the said bottom being located over the scouring-board, which is arranged to slide in the 15 box under the bottom to receive the dust from the grater, and the box is mounted on rockers to enable the brick to be ground by rocking the box, to shift the brick forward and backward along the grater without handling the 20 brick, to avoid getting the brick-dust on the hands, all as hereinafter fully described.

Reference is to be had to the accompanying drawings, forming part of this specification, in which similar letters of reference indicate corresponding parts in all the figures.

Figure 1 is a perspective view of my combined knife-brick box and grinder, with the cover of the box removed. Fig. 2 is a perspective view of the cover of the box, and 25 Fig. 3 is a longitudinal sectional elevation of the box and grinder.

In any suitable box, *a*, I provide a grating-bottom, *b*, of any approved kind, adapted to 30 grind a knife-brick, *c*, by shifting the brick along the grater, said grater being located 35 above a chamber, *d*, in which the scouring-

board *e* may slide to be kept in place and to receive the brick-dust falling through the grater. The box is provided with a sliding cover, *f*, to close in the brick, and at one end 40 of the box is a cell, *g*, for holding the cork, chamois-skin, or other rubber to be used in the scouring process.

The brick may be shifted along the grater by hand for grinding off the dust as wanted; 45 but I have arranged the box on rockers *h*, adapted to enable the box to be tilted forward and backward on the rockers, so that the brick will be made to slide forward and backward along the grater without touching the brick 50 with the hands and without opening the box, thus making a much neater and cleaner device than if the brick were shoved by hand.

Having thus described my invention, I claim as new and desire to secure by Letters Patent— 55

1. The brick-holding box *a*, having a grater-bottom, *b*, on which to grind the brick in its holding-box, said box *a* also having a scouring-board chamber, *d*, under the grater-bottom, in which to place the board *e*, for keeping 60 and for receiving the dust from the grater, substantially as described.

2. The brick-holding box *a*, having a grater-bottom, *b*, on which to grind the brick in the box, and said box *a* being arranged on rockers *h* to grind the brick by rocking the box, 65 substantially as described.

JOHN F. WOOD.
